[57] CLAIM

The ornamental design for a travelling carrier for heating elements in a paint spray booth, substantially as shown.

DESCRIPTION

FIG. 1 is a perspective view of a travelling carrier for heating elements in a paint spray booth, showing our new design;
FIG. 2 is a left side elevational view thereof;
FIG. 3 is a right side elevational view thereof;
FIG. 4 is a top plan view thereof;
FIG. 5 is a front elevational view thereof;
FIG. 6 is a rear elevational view thereof; and
FIG. 7 is a bottom plan view thereof.

FIG. 5

FIG. 6

FIG. 7
